HENRY R. MERSELES, OF BRONXVILLE, NEW YORK, ASSIGNOR TO HERBERT E. MERSELES, OF BRONXVILLE, NEW YORK.

WASHING MACHINE.

Application filed August 17, 1922. Serial No. 582,396.

This invention relates to dish washing machines, and aims to provide a small, compact, effective machine of this class for domestic use, although many features of the invention are also applicable to larger dish washing machines.

An object of the invention is to provide a unitary structure for directing a washing fluid and a rinsing fluid against the articles to be washed, and so arranged that the rinsing fluid does not come into contact with any parts of the structure with which the washing fluid has been in contact. This has the advantage of preventing the rinsing fluid from becoming soiled by the material which has been removed from the dishes by the washing fluid.

A further object of the invention is to provide a dish washing machine with a rotary projector for directing the washing fluid against the dishes, and so arranged that its rotation is caused by the impulse of the fluid forced into the projector as well as by the reaction of the fluid discharged by the projector. Since it is thus not necessary to rely solely upon the reaction of the fluid discharged to rotate the projector, the discharge nozzles of the projector may be inclined so as to strike the dishes most effectively.

A further object of the invention is to provide rotary projectors for directing fluids with equal effectiveness against all the soiled surfaces of the articles.

A further object of the invention is to secure a thorough distribution of the rinsing fluid over the articles while, at the same time, utilizing a small amount of rinsing fluid supplied under a low pressure. This has the advantage of enabling the rinsing fluid to be furnished from a domestic hot-water supply.

A further object of the invention is to provide a single control for the supply of washing and rinsing fluids and to connect this control with the cover of the tank in which the washing takes place in such manner that the cover cannot be opened without actuating the control to stop the washing. This has the advantage of preventing the spilling of the washing fluid when the cover of the tank is opened.

A further object of the invention is to provide a support for the dishes to be

washed which will retain them in a position to receive the washing fluid most effectively, regardless of the manner in which they are placed in the support.

Other objects and advantages of the invention are hereinafter explained.

A dish washing machine embodying the invention in the form which I now consider best, includes a tank containing a support for the articles to be washed and provided at its top with a hinged cover. To the bottom of the tank is secured a compact mechanism which may be termed a "wash and rinse unit". This mechanism is provided with a control lever, by the manipulation of which the mechanism may be caused to project, first, a washing fluid, and, then, a rinsing fluid against the articles on the support.

The nature of the invention may best be understood by a detailed description of a dish washing machine embodying it, which is shown in the accompanying drawings, in which:

Fig. 1 is a back elevation of the entire machine, showing the tank partly sectioned on the line 1—1 of Fig. 2.

Fig. 2 is a top view of the machine with a part of the cover broken away and the dish rack removed;

Fig. 3 is an enlarged, fragmentary, vertical section taken on the line 3—3 of Fig. 2 and showing the air vent between the cover and the tank;

Fig. 4 is a back elevation upon a larger scale than Figs. 1 and 2, sectioned on the line 1—1 of Fig. 2 and the line 4—4 of Fig. 8, and showing the bottom portion of the tank, the dish rack, and the wash and rinse unit;

Fig. 5 is an enlarged end view of the wash and rinse arms looking in the direction of the arrow 5 is Fig. 4;

Fig. 6 is an enlarged side view of one of the rinse arm nozzles partially sectioned on the plane of its discharge slit;

Fig. 7 is an enlarged, fragmentary section on the line 7—7 of Fig. 4 showing the shape of the transverse portion of the rinse conduit within the neck of the pump;

Fig. 8 is a horizontal section on the line 8—8 of Fig. 4 with parts of the top and bottom of the pump casing broken away;

Fig. 9 is an enlarged, fragmentary, horizontal section on the line 9—9 of Fig. 4.

showing the hub of the wash projector and the deflectors therein;

5 Figs. 10 and 11 show a modified form of pump casing and rinse conduit, Fig. 10 being a horizontal section on the line 10—10 of Fig. 11, and Fig. 11 being a vertical section on line 11—11 of Fig. 10;

Fig. 12 is a top view of the dish rack;

10 Fig. 13 is a top view of the silver basket; Fig. 14 is a side view of the silver basket.

The dish washing machine shown in the drawings includes a tank T provided with a hinged cover C. In the upper portion 15 of the tank is seated a dish rack D. Secured in the bottom of the tank T is the wash and rinse unit U, which includes a pump P, a wash projector W, and a rinse projector R, all located within the tank T, 20 and an electric motor M located outside and below the tank. To the outside of the tank T is secured a control mechanism K for controlling the supply of washing fluid and rinsing fluid to the projectors W and R.

25 The tank T may be made of sheet metal or other convenient material. It is supported upon legs T¹, which are of such length that the top of the tank is at about the height of an ordinary kitchen table.

30 The side wall T² of the tank may be substantially cylindrical, as shown. The side wall T² has a very slight taper, so that the diameter of its upper edge is slightly larger than the diameter of its lower edge. The

35 side wall T² is provided with two spaced internal beads T³, T⁴. These beads are of the same depth, but owing to the slight taper of the side wall, the diameter of the inner edge of the upper bead T³ is slightly

40 larger than the diameter of the inner edge of the lower bead T⁴. The upper inclined surface T⁵ of the bead T³ co-operates with the cover C to form an air vent and water trap, as hereinafter described. The upper

45 surface T⁶ of the bead T⁴ provides a support for the dish rack D. The bottom T⁷ of the tank slopes downwardly toward the center of the tank. At the middle of the bottom is a round opening T⁸. The bottom 50 is formed to provide a horizontal, annular flange T⁹ around the opening T⁸.

The wash and rinse unit U has a stationary member or rigid frame U¹, which forms the stationary part or casing P¹ of the pump P and the casing M¹ of the motor M. A portion of the frame U¹ forms a closure for the opening T⁸ in the bottom of the tank T. In the unit shown in the drawing, this closure is formed by the bottom

60 P² of the pump casing. The pump bottom P² is provided near its outer edge with two holes U⁴, U⁵, the purpose of which is hereinafter explained. The rotary members of the unit are supported on the rigid frame

65 U¹. These include the motor armature

and the pump impeller P³ and a common vertical shaft U² on which they are mounted, the wash projector W, and the rinse projector R. The shaft U² enters the pump casing P¹ through a central hole P⁴ 70 in the bottom P² of the pump casing. The lower portion of the hole P⁴ is enlarged to provide space for a stuffing box P⁵ which provides a bearing for the shaft U². The motor casing M¹ provides additional bearings for the shaft U². The wash projector W is mounted on the pump casing P¹, and the rinse projector R is mounted on the wash projector W. The wash and rinse unit U may be completely assembled before 80 it is applied to the tank T. After the unit has been assembled, it is placed in the tank and the motor M is passed through the hole T⁹ so that the peripheral portion of the bottom P² rests upon the flange T⁹. It is secured to this flange by stud bolts U⁷ and, if desired, may also be soldered to the bottom of the tank. The unit is placed in the tank in such position that the holes U⁴, U⁵ 85 in the bottom P² are brought into alignment with corresponding holes in the flange T⁹. A drain pipe O is connected with the opening U⁵. In the upper end of this drain pipe is seated the lower end O² of an overflow pipe O¹. The lower end of the overflow pipe O¹ fits tightly enough in the upper end of the drain pipe O to prevent leakage between them, while at the same time the overflow pipe O¹ may be lifted out 90 when desired. When the overflow pipe O¹ 95 is inserted in the drain pipe O as shown in the drawings, the upper end O³ of the overflow pipe O¹ is on a level with the upper part of the pump casing P¹. The hole U⁴ provides for the entrance into the tank of 100 a rinse supply conduit, which is herein- 105 after described.

The motor M is of the usual construction. It is supplied with electricity through leads M², which pass through a switch M³. The 110 casing M¹ of the motor is of the usual construction, except that its upper portion is provided with arms M⁴ whose upper ends are joined by a ring M⁵. This ring is secured to the bottom P² of the pump casing 115 P¹ by means of stud bolts M⁶. The upper portion of the motor casing M¹ is imperforate except for the central hole through which the shaft U² passes. A deflector U⁸, 120 fixed on the shaft U² just above the top of the motor casing M¹, prevents any fluid which may leak through the stuffing box P⁵ from entering this hole in the top of the motor casing.

The fixed portion or casing P¹ of the 125 pump P is formed to provide a bottom P², an impeller-enclosing portion P⁷ and a discharge conduit or neck P⁸. The pump casing may conveniently be formed of three 130 castings, as shown in Fig. 4, one of these

forming the bottom P^2 , the annular partition P^9 , which is the bottom of the impeller-enclosing portion P^7 , and fins P^{10} connecting these parts; the second casting forming the 5 upper part P^{11} of the impeller-enclosing portion P^7 ; and the third casting forming the discharge neck P^8 . The intake openings of the pump casing P^1 comprise the space provided between the annular flange P^6 and 10 the bottom P^2 of the pump casing and between the fins P^{10} . It will be noted that this intake opening communicates with the bottom of the tank and is positioned well below the top O^8 of the overflow pipe O^1 . 15 The discharge opening of the pump casing P^1 is located at the upper end of the discharge neck P^8 .

The pump impeller P^3 , which is fixed on the upper end of the shaft U^2 which is in 20 line with the center of the discharge opening of the pump casing, is provided with a top flange P^{12} and with spiral blades P^{13} depending from this flange and preferably formed integral with it. Fixed in the 25 pump casing P^1 , above the impeller flange P^{12} , are spiral blades P^{14} , which serve to direct the water thrown outwardly by the impeller blades P^{13} into the discharge neck P^8 . The impeller P^3 is rotated in a clockwise direction (looking from the top) by 30 the motor M , and the impeller blades P^{13} and the fixed blades P^{14} are so positioned that the water which is forced into the neck P^8 is given a swirling motion in a clockwise direction looking from the top (see 35 Fig. 8).

The wash projector W consists, in the form illustrated, of two hollow arms W^1 , W^2 , which project radially from a central 40 hub W^3 . The bottom end of the hub W^3 is open and forms the intake opening of the projector W . The hub W^3 is rotatably mounted on a bearing surface P^{15} provided at the upper end of the discharge neck P^8 45 of the pump casing P^1 with its intake opening in communication with the discharge opening of the pump casing. A vertical bearing surface P^{16} formed on the neck P^8 serves to center the hub W^3 and to retain 50 it co-axial with the shaft U^2 .

Curved deflectors W^6 , W^8 project into the hub W^3 from the inner ends of the arms W^1 , W^2 , respectively. These deflectors are arranged, as best seen in Fig. 9, so that they 55 direct the stream of fluid which is forced into the hub through the neck of the pump casing, and which is swirling in a clockwise direction, radially outward into the arms W^1 , W^2 . It follows that the stream of fluid is not required to turn any sharp corners to enter the wash arms W^1 , W^2 . The deflectors have been found to increase 60 the effective pressure of the fluid in the arms to a very material extent.

65 It is apparent, also that the impingement

of the swirling fluid upon the deflectors W^6 , W^8 , tends to rotate the projector W in a clockwise direction.

The upper sides of the arms W^1 , W^2 are provided with discharge nozzles W^7 , W^8 , W^9 , W^{10} . These nozzles are provided with radial discharge slots W^{11} and are so formed that they project fluid in the form of fan-like sprays.

The nozzles W^7 , W^8 , W^9 , W^{10} are placed 75 at progressively decreasing distances from the axis of the hub W^3 so that they move in equally spaced, concentric circles as the projector rotates. The nozzles are so positioned on the two arms that the tendency of 80 the reaction of the fluid discharge through the nozzles W^7 and W^{10} of the arm W^1 to tip the arm W^1 downwardly in the plane of the axis of the projector is counterbalanced by the tendency of the reaction of the fluid discharged through the nozzles W^8 , W^9 of the arm W^2 to tip that arm down. When the nozzles are all of the same size and are positioned so as to rotate in equally spaced, 85 concentric circles, as in the form illustrated, this balancing is obtained by placing the nozzle W^7 , which is most distant from the axis, upon one of the arms, placing the nozzles W^8 and W^9 , which are the two next most distant from the axis, upon the other 90 arm, and by placing the nozzle W^{10} , which is nearest to the axis, upon the same arm as the nozzle W^7 . In order to obtain such balancing, it is, however, not necessary that four nozzles be used, as illustrated in the 100 drawing. I have found that in order to obtain such balancing with nozzles of equal size positioned at progressively decreasing distances from the axis, it is necessary that the total number of the nozzles be a multiple 105 of four or one less than a multiple of four, and that the nozzles be distributed on the two arms according to the following rule: Place the most distant nozzle upon one arm, the next two nozzles upon the other arm, the 110 next two nozzles upon the first arm, the next two upon the second arm, and so on, until all the nozzles have been located.

The arms W^1 , W^2 are of the same length and of the same internal volume, so that the 115 weights of the arms and the fluid which they contain are equal. The projector is thus balanced, both with respect to reaction and with respect to weight, so that it has no tendency to tip in any direction.

The nozzles W^7 , W^8 , W^9 , W^{10} , are all inclined to the axis of the projector. The nozzle W^7 of the arm W^1 and the nozzle W^9 of the arm W^2 are inclined so as to project fluid rearwardly as the projector rotates in a 125 clockwise direction, while the nozzle W^{10} of the arm W^1 and the nozzle W^8 of the arm W^2 are inclined so as to project fluid forwardly, that is, ahead of the arms, as the projector rotates in a clockwise direction.

The angles at which the nozzles are inclined to the axis are such that the fluid projected by the forwardly inclined nozzles W^8 and W^{10} is moving at the same angle to the vertical as the fluid projected from the rearwardly inclined nozzles W^7 , W^9 when the fluid from the nozzles strikes the dishes or other articles supported in the rack D. It is to be noted that the angle of incidence of the fluid discharged from a nozzle upon a vertical plane in the dish rack D depends upon two factors, namely, the inclination of the nozzle and the rotary movement thereof. In order to make the angles of incidence of the fluid discharged from the rearwardly and forwardly inclined nozzles substantially equal, I have found that it is necessary to incline the rearwardly inclined nozzles to the axis of the projector at substantially twice as great an angle as that at which the forwardly inclined nozzles are inclined to the axis of the projector. Thus, in the particular machine illustrated, in which the wash projector rotates at a rate of approximately thirty (30) revolutions per minute, the rearwardly inclined nozzles W^7 , W^9 are inclined at 15° to the axis of the projector, while the forwardly inclined nozzles W^8 , W^{10} are inclined at an angle of $7\frac{1}{2}^\circ$ to the axis of the projector (see Fig. 5). The arrangement and inclination of the nozzles described has been found to project the washing fluid with equal effectiveness against both sides of articles which are supported in the rack D in such manner that their soiled surfaces are substantially vertical.

Owing to the fact that the rearwardly inclined nozzles W^7 , W^9 are more inclined than the forwardly inclined nozzles W^8 , W^{10} , and that the sum of the distances of the rearwardly inclined nozzles from the axis is greater than the sum of the distances of the forwardly inclined nozzles from the axis, the resultant reaction of the fluid discharged through all the nozzles tends to cause a forward rotation of the projector, that is to say, a rotation in a clockwise direction (looking from the top). It is apparent, therefore, that the rotation of the projector is caused both by the impingement against the deflectors W^5 , W^6 of the swirling stream of fluid forced into the projector and by the reaction of the fluid discharged by the projector, and that these two factors have an additive effect.

The outer ends of the arms W^1 , W^2 are closed by plugs W^{12} , which are detachably secured to the outer ends of the arms so that they may be removed to permit the cleaning of the arms and nozzles.

While the particular construction of the wash projector W, which is illustrated in the drawing, may be modified without changing the operation of the projector, this construction embodies a number of advan-

tageous features. Thus, in the form shown, the hub W^3 consists of a casting of which the deflectors W^5 , W^6 are integral parts while the arms W^1 , W^2 are formed separate from the hub, and the nozzles are stamped of separate pieces of metal and provided with cylindrically curved flanges W^{13} , which are sweated or otherwise secured to the arms about lateral holes W^{14} provided therein. It is, however, not essential that the arms W^1 , W^2 be formed of pieces of metal separate from the hub W^3 , and it should be understood, therefore, that the use of the word "hub" and the word "arms" in the claims of this application is not intended to imply that the hub is necessarily made separate from the arms, for it may be merely the axial portion of an integral member which forms both the arms and the hub.

The rinse projector R consists of hollow arms R^1 , R^2 , projecting radially outward from a central hub R^3 , which is rotatably mounted upon the upper end of the hub W^3 of the wash projector W. In order to eliminate friction between the hubs, a self-lubricating washer R^4 , made of brass impregnated with graphite, is seated in a recess in the upper end of the hub W^3 and the lower end of the hub R^3 rests upon this washer.

Rinsing fluid is supplied to the rinse projector R through a rinse supply conduit. The rinse supply conduit includes a horizontal pipe R^5 located below the bottom of the tank T and connected with a source of rinsing fluid, such as hot water, outside the tank. In this pipe R^5 is a whistle valve R^7 which is actuated by the control mechanism K. Connected to the inner end of the horizontal pipe R^5 is a vertical pipe R^6 which extends into the tank T from the bottom, passing through a hole in the flange T^9 of the tank bottom and the aligned hole U^4 in the bottom P^2 of the pump casing. A curved pipe R^8 has one of its ends secured to the upper end of the pipe R^7 by a detachable pipe union R^8' . The other end of the curved pipe R^8 connects with a conduit R^9 which extends through the wall of the neck P^8 and radially inward to the center of the pump casing. The conduit R^9 is preferably formed as an integral part of the casting which forms the neck P^8 . The conduit R^9 is flared or flattened in a direction slightly inclined to the horizontal, as shown in Fig. 7, so that it does not materially obstruct the swirling of the washing fluid in the neck P^8 .

A pipe R^{10} projects upwardly from a hole formed in the upper side of the conduit R^9 near its inner end. The pipe R^{10} is located in the center of the neck P^8 and in line with the shaft U^2 . It projects upwardly through a central hole in the upper end of the wash hub W^3 and through central holes in the upper and lower ends of the rinse hub R^3 . The engagement of the rinse hub with the

upper portion of this pipe serves to center the rinse projector R. Lateral holes R¹¹ in the pipe R¹⁰ within the rinse hub R³ permit the rinsing fluid to enter the hub of the 5 rinse projector. The upper end of the pipe R¹⁰ is closed by a detachable plug R¹². This plug has a head or flange R¹³ which extends over the upper end of the rinse hub R³. This head serves to prevent upward 10 movement of the projectors W and R under the pressure of the fluid which is forced into the wash projector during the operation of the machine. When the plug R¹² is removed, the projectors R and W may be lifted off 15 for the purpose of giving them a thorough cleaning. The hub R³ of the rinse projector is provided with two upwardly projecting bosses R¹⁴ which engage the top of the hub W³ of the wash projector and prevent the 20 plug R¹² from being replaced in position in case the rinse projector R is put back upside down.

It may be noted that the portion of the pipe R¹⁰ which is within the wash hub W³ 25 co-operates with the deflectors W⁵, W⁶ in directing the swirling stream of fluid which is forced into the wash hub W³ radially outward into the wash arms W¹, W².

The rinse projector R is provided with 30 four discharge nozzles R¹⁵, which are positioned and inclined in the same manner as the nozzles W⁷, W⁸, W⁹, W¹⁰ of the wash projector. In consequence, the rinse projector R is balanced, and is rotated by the 35 reaction of the fluid discharged from it, and the rinse fluid is distributed with equal effectiveness on both sides of the articles in the same way as the wash fluid.

The rinse nozzles are different in form from 40 the wash nozzles. They are formed so as to project flat, fanlike sprays even when operated with a small quantity of fluid supplied under low pressure. As best seen in Fig. 6, each rinse nozzle R¹⁵ has a general 45 conical form and is provided at its upper end with a short diametrical discharge slit R¹⁶. The material of the nozzle is pressed in at each end of the slit R¹⁶, so as to form an inwardly projecting deflector R¹⁷ just inside 50 each end of the slit. The fluid flowing outwardly along opposite walls of the rinse nozzle is directed inwardly by the deflectors R¹⁷ so that two streams of the fluid impinge 55 against each other just inside the slit R¹⁶. This has been found to result in projecting 60 the fluid through the slit in the form of a very thin, fan-like spray. The ends of the rinse arms R¹, R² are provided with detachable plugs R¹⁸ similar to the plugs W¹².

A modified form of the portion of the 65 rinse conduit within the pump casing and a corresponding modification of the pump casing is illustrated in Figs. 10 and 11. In this form, the pipe R⁸ is connected with a conduit R⁹, which passes

through the pump casing P¹ below the neck P⁸ thereof and on a level with the fixed spiral blades P¹⁴ of the pump casing. One of these blades P¹⁴ is extended to the center of the casing and the conduit R⁹ extends 70 along this blade. As in the form first described, a pipe R¹⁰ extends upwardly from the inner end of the conduit R⁹ and passes through the projectors W and R. In the modification shown in Figs. 10 and 11, the 75 neck P⁸ of the pump casing and the upper part P¹¹ of the impeller-enclosing portion P¹ are formed of a single casting, and the blades P¹⁴ and the conduit R⁹ are integral 80 parts of this casting. This construction ensures a proper centering of the pipe R¹⁰ with the vertical bearing surface P¹⁶ of the neck P⁸. The position of the conduit R⁹ shown in the modification has the advantage of preventing this conduit from in 85 any way interfering with the swirling of the fluid in the pump casing above the impeller.

The controlling mechanism K is so arranged that manipulation of a single control lever K¹ serves to control both the supply of rinsing fluid to the rinse projector and the supply of washing fluid to the wash projector. The control lever K¹ is fulcrumed at its lower end to a support K² projecting 90 outwardly from the side wall T² of the tank T near the top of the tank. A connecting rod K³ has its upper end pivotally secured to the control lever K¹ at a point spaced from the fulcrum of the lever. The lower end of the connecting rod K³ is slidably 95 mounted in a hole in a bracket K⁴ which is secured to an arm K⁵ extending downwardly from the tank T. Mounted on the lower end of the connecting rod below the bracket K⁴ is an operating head K⁶ having a horizontal 100 slot K⁷ in its inner side. The portion K⁸ of the head below the slot K⁷ projects further than the portion K⁹ of the head above the slot. The switch M³, to which the motor leads M² are connected, is mounted on the 105 arm K⁵ and provided with an operating lever K¹⁰ which projects into the slot K⁷ of the head K⁶ when the head is raised against the lower side of the bracket K⁴. The switch 110 is so arranged that when its operating lever K¹⁰ is in this position, the switch is closed, while, when the operating lever is turned 115 downwardly the switch is opened.

The whistle valve R⁷ in the rinse pipe R⁵ is secured to the lower end of the arm K⁵. 120 The operating pin K¹¹ of the whistle valve projects upwardly under the head K⁶. The whistle valve R⁷ is arranged, as is usual in such valves, so that it is opened when the pin K¹¹ is depressed. A spring in the whistle valve keeps the valve normally closed and the pin K¹¹ normally raised.

When the control lever K¹ is in raised position, as shown in Fig. 1, the head K⁶ is in 130 its raised position and the operating lever

K¹⁰ of the switch **M³** is raised so as to close the switch. When the lever **K¹** is moved downwardly and outwardly, the first effect is for the portion **K⁸** of the head **K⁶** to depress the operating lever **K¹⁰**, opening the switch **M³** and stopping the motor. A further downward movement of the lever **K¹** and the head **K⁶** causes the lower surface of the head to depress the pin **K¹¹** of the whistle valve against the spring in the valve and to open this valve so that rinsing fluid flows through the rinse pipe **R⁵**. When the lever **K¹** is released after being fully depressed, the lever and head are raised to their "neutral" position by the spring of the whistle valve, so that neither the wash projector nor the rinse conduit is in operation. If the lever is moved upward from its neutral position, the portion **K⁸** of the head **K⁶** engages the operating lever **K¹⁰** of the switch **M³** and raises it so as to close the switch and start the motor.

It should be noted that the operating lever **K¹** is so formed and positioned that when it is placed so as to actuate the motor to supply washing fluid to the wash projector, its upper end projects over the cover **C** of the tank. If the cover is accidentally opened while the motor and wash projector are in operation, the initial opening movement of the cover forces the lever **K¹** into its neutral position, stopping the motor and cutting off the supply of washing fluid to the wash projector. This prevents a spilling of the washing fluid in case the cover is accidentally opened without first stopping the motor.

The cover **C** is arranged to prevent the escape of the washing and rinsing fluids discharged by the projectors **W** and **R**, while permitting the escape of air from the tank. When the wash projector is placed in operation, the air in the tank is heated rapidly from the room temperature to the temperature of the hot wash fluid. This causes a rapid expansion of the air in the tank. If the tank is provided with an ordinary close-fitting cover, the expanding air will raise the cover and carry out some of the washing fluid with it as it escapes from the tank. A feature of the present invention consists in arranging the cover so that the air is allowed to escape but cannot carry with it any of the washing fluid.

The cover **C** is secured to the outer side of the cylindrical wall **T²** of the tank **T** by means of a hinge **C¹** at the back of the tank. The cover is formed to provide an outwardly projecting peripheral flange **C²**, which extends over the upper edge **T¹⁰** of the cylindrical wall **T²** of the tank when the cover is closed. The lower surface **C³** of the flange **C²** is substantially horizontal when the cover is closed and extends inwardly some distance inside the cylindrical wall of

the tank. From the inner end of the surface **C³** depends a cylindrical skirt **C⁴**. The lower edge **C⁵** of the skirt **C⁴** engages two supports **T¹¹** when the cover is closed. These supports may consist, as shown, of short, curved rods secured to the inside of the wall **T²** of the tank at or near the upper edge of the inclined surface **T⁵** of the bead **T³**.

When the cover **C** is closed, it is supported by the hinge **C¹** and by the supports **T¹¹** in such manner that the lower edge **C⁵** of the skirt **C⁴** is spaced slightly above the inclined surface **T⁵** of the bead **T³**, while the bottom surface **C³** of the flange **C²** is spaced slightly above the upper edge **T¹⁰** of the wall **T²** of the tank. The lower edge of the skirt **C⁴** may be rolled to form a small projection **C⁶** which is close to the wall **T²** of the tank but spaced from this wall when the cover is closed.

It will now be noted that, as a result of the arrangement described, when the cover is closed a space or passage is provided between the upper portion of the wall **T²** of the tank and the cover extending substantially all the way around the tank. This passage is crooked, that is to say, a straight line cannot be drawn through it from within the tank to a point outside of the tank. It contains two necks, one, **C⁷**, formed between the lower edge **C⁵** of the skirt **C⁴** and the inclined surface **T⁵** of the bead **T³** and between the projection **C⁶** and the wall of the tank, and the other, **C⁸**, between the lower surface **C³** of the flange **C²** and the upper edge **T¹⁰** of the wall of the tank. The space **C⁹** between these necks is much wider than either of the necks.

When the wash projector **W** is placed in operation, the expanding air escapes through the crooked passage provided between the cover **C** and the upper portion of the wall **T²** of the tank. The washing fluid which is projected towards each point of the periphery of the cover as the arm rotates is trapped in the space **C⁹**. This space is of such size that before the point of it towards which the washing fluid is projected at any moment is completely filled, the turning of the projector has directed the fluid towards a different point of the periphery of the cover so that the waters trapped at the first point in the space **C⁹** runs back into the tank.

The upper surface **C¹⁰** of the cover is upwardly inclined toward the center of the cover. This adds to the strength of the cover and also facilitates the moving of the control lever **K¹** into its neutral position when the cover is accidentally raised during the operation of the wash projector **W**.

The dish rack **D** is arranged to hold dishes placed in it with their soiled surfaces substantially vertical, regardless of the manner in which the dishes are placed in the

rack. This results in locating the soiled surfaces of the dishes in position to receive the fans of fluid projected from the inclined nozzles of the projectors at such an angle 5 that the washing fluid peels the dirt from the surfaces. The dish rack serves also to retain cups and glasses with their bottoms at an angle to the horizontal, so that they are drained effectively after they have been 10 rinsed.

An important feature of the dish rack is that while it is strong and of simple construction and does not obstruct the sprays of washing and rinsing fluid, it is, nevertheless, arranged so that the articles to be washed cannot come into contact with any metal parts. This avoids chipping and staining the dishes.

The dish rack D, shown in the drawings, 20 has one side D¹ adapted to hold plates and its opposite side D² adapted to hold cups and glasses.

The bottom of the dish rack is formed of 25 open wire-work, which may conveniently be termed wire mesh. In the form shown, this bottom is formed by three circular hoops of wire D⁴, D⁵, D⁶, and a plurality of radial wires D⁷, D¹⁴.

The radial wires D⁷ on the plate side D¹ 30 of the dish rack are horizontal and are comparatively closely spaced. They are soldered or otherwise secured to the hoops D⁴, D⁵, D⁶.

Each of the radial wires D⁷ is bent to 35 form a plurality of upwardly projecting loops D⁸. The portions of the radial wires forming the sides of each loop are pressed together so that the loops in effect form pins projecting upwardly from the bottom of the 40 rack. The outer ends of the radial wires D⁷ are also turned upwardly to form peripheral pins D⁹. Over the bottom of the side D¹ of the rack is formed a net-work of non-metallic material. In the form shown, 45 this net-work consists of radial and circumferential reeds D¹⁰, which are secured to the radial wires D⁷. The reeds D¹⁰ prevent the edges of the plates from coming in contact with the metal wires which form the 50 bottom of the rack. Each of the pins D⁸ is covered with a casing D¹¹ of soft material, which may conveniently take the form of a rubber tube. The casings D¹¹ prevent the dishes from coming into contact with the 55 metal pins D⁸.

The pins D⁸ are so positioned as to leave 60 long, narrow spaces between them extending in numerous different directions. This arrangement permits the placing of plates between the pins when the dishes are turned either circumferentially or radially or at various different angles to the circumference or the radii of the rack. The pins are placed at such a distance from each

other that plates placed in any of these 65 directions are held substantially vertical.

The radial wires D¹⁴ of the cup and glass side D² of the dish rack are inclined upward towards the outer edge of the rack. They have, at their outer ends, vertically 70 depending portions D¹⁶ which are secured, at their lower ends, to the outer bottom hoop D⁴. The radial wires D¹⁴ are secured near their inner ends to the inner hoop D⁶. These wires are secured at an intermediate point 75 to the middle hoop D⁵, which is bent upwardly at this side of the dish rack. Loops having their sides closely spaced are formed in the radial wires D¹⁴, so as to form pins D¹⁶, similar to the pins D⁸ but more widely 80 spaced, and peripheral pins D¹⁷.

The inclined radial wires D¹⁴ are covered with a net-work of circumferential and radial reeds D¹⁸ which form an inclined support for the bottoms of cups and glasses 85 and maintain these articles out of contact with the radial wires. The pins D¹⁶ prevent these articles from sliding inwardly on the inclined surface. Like the pins D⁸, they are provided with soft tubular casings D¹⁹. 90 The dish rack is provided with a supporting wire hoop D²⁰ which is secured to the outer sides of the peripheral pins D⁹ and to the outer sides of the depending wires D¹⁶ a little above the bottom of the rack. The dish rack 95 may be strengthened by an additional hoop D²¹ above the hoop D²⁰ and secured in the same manner. Circumferential reeds D²² may be secured to the inside of the peripheral pins D⁹ and the inside of the peripheral pins D¹⁷ to prevent the dishes from 100 coming into contact with any wire at the periphery of the rack. The rack is provided with two handles D²³ to facilitate lifting it.

The outside diameter of the hoops D²⁰ and D²¹ is slightly less than the diameter of the inner edge of the bead T³ and slightly greater than the diameter of the inner edge of the bead T⁴. When the rack is placed in the tank, therefore, it passes the bead T³, and 110 its supporting hoop D²⁰ rests upon the inclined surface T⁶ of the bead T⁴. This holds the rack with its bottom horizontal and slightly above the rinse projector R.

It will be understood that if the number 115 of plates or the number of cups and glasses to be washed is sufficient to justify it, the machine may be provided with dish racks having both sides similar to the side D¹ of the rack shown for the support of plates or with both sides similar to the side D² for the support of cups and glasses.

In order to provide for the support of 120 table silver, an open-mesh basket D²⁴ is provided. As shown in Figs. 13 and 14, this basket is wedge-shaped, so that it may be inserted between the pins D⁸ of two of the 125 adjacent radial wires D⁷ of the side D¹ of

the dish rack. When so inserted, it rests upon the reeds D^{10} and is held securely in position by the pins D^8 . The table silver may be placed in the basket either before 5 or after the basket has been thus inserted in the dish rack.

Strainer pans S are provided for preventing solid matter removed from the dishes by the washing fluid from falling to the bottom 10 of the tank and being drawn into the intake opening of the pump or clogging the drain pipe O .

In the form shown, there are three strainer pans S , which are segmental in form. The 15 peripheral portion of each pan rests upon the peripheral portion of the bottom of the tank, while the inner edge of each pan is supported on a circumferential flange P^{20} formed on the outside of the neck P^8 of the 20 pump casing. Each strainer pan is provided at one of its radial edges with a flange S^1 , which is off-set upwardly so as to overlap the radial edge of the adjacent pan, thus preventing any solid matter from passing 25 between the pans. In order to facilitate their removal from the tank for the purpose of cleaning them and the parts under them, each strainer pan S is provided with a handle S^2 .

30 The use and operation of the dish washing machine which has been described is as follows:

The first step in using the machine is to 35 fill the bottom of the tank up to the level of the top of the overflow pipe O^1 with washing fluid. This is done by pressing the control lever downward from its neutral position so that the head K^6 depresses the pin K^{11} and allows hot water or other rins- 40 ing fluid to enter the tank through the rinse projector R . The lever K^1 is held down until the bottom of the tank is filled to the level of the top of the overflow pipe O^1 and then allowed to reassume its neutral 45 position. If hot water is used as a rinsing fluid, a detergent is then added to the water in the bottom of the tank so as to make this water effective as a washing fluid.

The dish rack D is then placed in the tank 50 with its supporting hoop D^{20} resting on the bead T^4 . The dishes and other articles to be washed may be placed in the dish rack between the pins D^8 and the pins D^{16} either before or after the rack is placed in the tank.

55 The cover C of the tank is then closed and the control lever K^1 is moved to its upper position, causing the head K^6 to close the switch M^3 and place the motor M and pump P in operation. The pump draws the washing fluid from the bottom of the tank and forces it into the wash projector W , whence 60 it is projected against the dishes or other articles in the dish rack D . The washing fluid projected falls back from the dishes and 65 from the inner walls of the tank and cover

into the bottom of the tank and may thus be used over and over again as long as the pump is kept in operation. It has been found, however, that owing to the effective manner in which the washing fluid is projected against the dishes, only a minute or 70 two is required to thoroughly cleanse them.

During the washing operation, the wash projector W rotates rapidly. Owing to the slight friction between the hubs W^3 and R^3 , 75 the rinse projector R tends to rotate slowly in the same direction as the wash projector W . It has been found, however, that the rinse projector in no way interferes with the fluid projected from the nozzles of the wash projector, as the force of the sprays of washing fluid is such that they immediately turn the rinse projector out of the way, in case the rinse projector happens at any time to be placed nearly in line with the wash projector. 85

After the washing is thus completed, the lever K^1 is pushed down sufficiently to open the valve R^7 admitting clean rinsing fluid to the rinse projector R . This fluid, which is usually hot water, is thoroughly distributed over the dishes and other articles by the rinse projector and serves to remove from them all the washing fluid with which they are wet after the washing operation. 90 During the rinsing, the rinse projector R is rotated by reaction, while the wash projector W remains stationary. Only a few seconds are required for the rinsing operation, after which the lever K^1 is allowed to reassume 100 its neutral position. Owing to the position of the dishes and cups and glasses in the dish rack D , the rinsing fluid drains off them as soon as the rinsing operation is stopped. It has been found that if a very 105 hot rinsing fluid is used, the draining is so effective that the dishes are practically dry when removed from the tank, so that no wiping of them is necessary. The rinsing fluid is so effectively distributed by the projector 110 R that only one or two quarts of it need be used to rinse the articles effectively. This amounts to about one-fifth of the quantity of 115 washing fluid in the bottom of the tank.

After the washing and rinsing, the cover 115 C is opened, the lever K^1 being in its neutral position, so that it does not interfere with the movement of the cover, and the dish rack D is lifted from the tank by its handles, or, if preferred, the dishes are removed 120 individually from the dish rack while the latter remains in the tank.

If desired, several batches of dishes or other articles may be washed in succession without draining the washing fluid in the 125 bottom of the tank. This is because the solid matter removed from the dishes is retained upon the strainer pans S and also because any grease which may be floating on the washing fluid in the bottom of the 130

tank after the washing operation is decanted through the overflow pipe during the rinsing operation. Furthermore, the hot fluid which flows to the bottom of the tank during each rinsing operation serves to keep hot the fluid retained in the bottom of the tank for washing purposes.

After all the dishes or other articles have been washed, the strainer pans S are removed 10 and the washing fluid remaining in the bottom of the tank is drained off through the drain pipe O by lifting out the overflow pipe O¹. The tank and the apparatus in it may, if desired, then be washed by admitting additional rinsing fluid through the valve K¹ and the rinse projector.

From the above description, it will be apparent that the embodiment of the invention which has been illustrated and described is 20 a compact unitary machine, all of whose parts co-operate in the rapid and efficient cleansing of dishes and other articles. It should be understood, however, that many features of the embodiment described may, 25 under certain circumstances, advantageously be used independently, and these features in themselves constitute parts of my invention. It should be understood, also, that the invention is by no means limited to the particular form and arrangement of the parts 30 of the embodiment described except in so far as specified in the claims which follow.

What is claimed is:

1. A dish washing machine, comprising a 35 tank having an opening in its bottom, means for supporting the articles to be washed in the upper part of the tank, a wash and rinse unit having a rigid frame providing a closure for the opening in the tank and two 40 separate fluid conduits, one of which extends through said closure and is connected to a supply of rinsing fluid, means for drawing washing fluid from the bottom of said tank and forcing it through the other conduit, 45 and two coaxial rotary fluid projectors supported adjacent to each other on said frame and having intake openings communicating with said fluid conduits respectively and discharge openings directed toward the articles 50 on said support.

2. In a washing machine, the combination of two adjacent coaxial rotary projectors, a conduit for supplying a fluid to one of the projectors, and a conduit for supplying another fluid to the second projector, the second conduit including a pipe extending within the first conduit and axially through the first projector.

3. In a dish washing machine, a wash and 60 rinse unit comprising a frame, a fluid projector rotatably mounted thereon, a second projector rotatably mounted on said first projector, and separate fluid conduits communicating with said projectors respectively.

4. In a dish washing machine, a wash and

rinse unit comprising a rigid frame providing a central conduit and an annular conduit surrounding said central conduit, a projector mounted on said frame and having an intake opening in communication 70 with said annular conduit, and a second projector mounted on said first projector and having an intake opening in communication with said central conduit.

5. In a washing machine, the combination 75 of a projector comprising a rotatable hollow hub and hollow arms extending radially therefrom and having discharge openings, a second projector having a hollow hub coaxial with the hub of the first projector and 80 hollow arms extending radially therefrom and containing discharge openings, means for supplying a washing fluid to the hub of one of said projectors, and a conduit for supplying a rinsing fluid to the hub of the other projector, said conduit including a 85 pipe extending axially through the hub of the first projector.

6. In a washing machine, the combination 90 of a supply conduit having a discharge opening, a projector comprising a hollow hub containing an axial intake opening and rotatably mounted on said supply conduit with its intake opening in communication with the discharge opening thereof and hollow 95 arms extending radially from said hub and containing discharge openings, a second projector comprising a rotary hollow hub coaxial with the hub of the first projector and hollow arms extending radially from said 100 second hub and containing discharge openings, and a pipe extending through the discharge opening of said supply conduit and axially through the hubs of both projectors, said pipe containing a lateral discharge 105 opening within the hub of the second projector.

7. In a washing machine, the combination 110 of a supply conduit having a discharge opening and providing a bearing surface surrounding said opening, a projector comprising a hollow hub having an open end rotatably mounted on said bearing surface and hollow arms extending radially from said 115 hub and containing discharge openings, a second projector comprising a rotary hollow hub coaxial with the hub of said first projector and hollow arms extending radially from said second hub and containing discharge openings, a pipe extending through the discharge opening of said supply conduit and axially through the hubs of both projectors, said pipe containing a lateral discharge 120 opening within the hub of the second projector.

8. In a washing machine, the combination 125 of a supply conduit having a discharge opening and providing a bearing surface around 130

the discharge opening of said supply conduit and axially through the hubs of both projectors, said pipe containing a lateral discharge opening within the hub of the second projector, and means mounted on said pipe beyond the hub of the second projector for restraining outward movement of the hubs.

said opening, a projector comprising a hollow hub having an open end rotatably mounted on said bearing surface and hollow arms extending laterally from said hub and containing discharge openings, a self-lubricating bearing washer seated on the outer end of said hub, a second projector comprising a hollow hub rotatably mounted on said bearing washer and coaxial with the hub of the first projector, and hollow arms extending laterally from said second hub and containing discharge openings, and a pipe extending through the discharge opening of said supply conduit and axially through the hubs of both projectors and the bearing washer, said pipe containing a lateral discharge opening within the hub of the second projector.

9. In a washing machine, a wash and rinse unit comprising a pump having a casing containing an upwardly directed discharge opening, a rotary projector having an axial intake opening and rotatably mounted on the pump casing with its intake opening in communication with the discharge opening of the casing, a second projector rotatably mounted on said first projector, and a pipe connected to a supply of rinsing fluid and extending into the pump casing and upward through the center of the discharge opening of the casing and through the first projector and communicating with the second projector.

10. In a washing machine, a wash and rinse unit comprising a pump casing having an upwardly directed discharge opening, a rotary impeller in said casing adapted to force a stream of fluid through said discharge opening, a rotary projector comprising a hollow hub having an axial intake opening and rotatably mounted on said casing and with its intake opening in communication with the discharge opening of the casing and hollow arms extending radially from said hub and having discharge openings, a second rotary projector comprising a hollow hub rotatably mounted on the hub of the first projector and hollow arms extending radially from said second hub and having discharge openings, and means for supplying fluid to said second projector comprising a pipe extending into the pump casing to the center thereof above the impeller and extending upwardly through the middle of the discharge opening and through the hub of the first projector and communicating with the hub of the second projector.

11. In a washing machine, the combination of a rotatably mounted hollow hub having an axial intake opening at one of its ends, hollow arms extending radially from said hub and containing discharge openings, means located outside the hub for forcing a swirling stream of fluid into said hub through its intake opening, and deflectors in

said hub positioned to cause a rotation of the hub and arms by the impingement thereon of the swirling fluid in the hub.

12. In a washing machine, the combination of a rotatably mounted hollow hub having an axial intake opening at one of its ends, hollow arms extending radially from said hub and containing discharge openings positioned and inclined so as to cause a rotation of the hub and arms by the reaction of the fluid discharged therethrough, means outside the hub for forcing into said hub through its intake opening a stream of fluid swirling in the direction of rotation of said hub, and deflectors in said hub positioned to accelerate the rotation of the hub and arms by the impingement of the swirling fluid upon them.

13. In a washing machine, the combination of a hollow hub having an axial intake opening, hollow arms extending radially therefrom and containing discharge openings, means for forcing a swirling stream of fluid into said hub, and a deflector extending into the hub from one side of the inner end of each of said arms and inclined so as to direct the swirling fluid in the hub into said arm.

14. In a washing machine, a washing unit comprising a pump casing having an upwardly directed discharge opening, a rotary impeller in said casing adapted to force a swirling stream of fluid therethrough, a hollow hub having an axial intake opening and rotatably mounted on the pump casing, coaxial with said impeller, and with its intake opening in communication with the discharge opening of the casing, hollow arms extending radially from said hub and containing discharge openings, and a deflector extending into the hub from one side of the inner end of each of said arms and inclined so as to direct the swirling fluid in the hub into said arm and to cause a rotation of the hub and arms by the impingement of the swirling fluid upon it.

15. In a washing machine, a washing unit, comprising a pump casing having an upwardly directed discharge opening, a rotary impeller in the casing adapted to force a swirling stream of fluid therethrough, a hollow hub having an axial intake opening and rotatably mounted on said casing, coaxial with said impeller, and with its intake opening in communication with the discharge opening of the casing, hollow arms extending radially from said hub and containing discharge openings, an axial member extending through said hub so as to displace the swirling fluid from the central portion of the hub, and a deflector in said hub extending inwardly from one side of each of said arms, terminating close to said axial member, and inclined so as to force the swirling fluid in the hub into said arm and

to cause the rotation of the hub and arms by the impingement of the swirling fluid upon it.

16. In a washing machine, a washing unit, comprising a pump casing having an upwardly directed discharge opening and providing a bearing surface around said opening, a rotary impeller in said casing adapted to force a swirling stream of fluid through said opening, a member fixed in said pump casing and extending from a wall thereof first inwardly above the impeller to the center of the casing and then upwardly through the center of the discharge opening, the inwardly extending portion of said member being formed so as not materially to obstruct the swirl of fluid in the casing, a hollow hub whose lower end is open and rotatably mounted on said bearing surface and whose upper end contains an axial hole surrounding the projecting portion of said fixed member, hollow arms extending radially from said hub and containing discharge openings, a deflector extending into the hub from one side of the inner end of each of said arms and inclined so as to direct the fluid swirling in the hub into said arm and to cause a rotation of the hub and arms by the impingement of the swirling fluid thereon, and means mounted on said fixed member above said hub to prevent upward movement thereof.

17. In a washing machine, a washing unit, comprising a pump casing having an upwardly directed discharge opening and providing a bearing surface around said opening, spiral vanes fixed in the upper portion of the casing to direct the fluid inwardly toward the discharge opening, a rotary impeller in said casing adapted to force a swirling stream of fluid through said opening, a member fixed in said casing and having a portion extending inwardly from the inner end of one of said spiral vanes and to the center of the casing, and a portion extending upwardly through the center of the discharge opening, a hollow hub whose lower end is open and rotatably mounted on said bearing surface and whose upper end contains an axial hole surrounding the projecting portion of said fixed member, hollow arms extending radially from said hub and containing discharge openings, a deflector extending into the hub from one side of the inner end of each of said arms and inclined so as to direct the fluid swirling in the hub into said arm and to cause a rotation of the hub and arms by the impingement of the swirling fluid thereon, and means mounted on said fixed member above said hub to prevent upward movement thereof.

18. In a washing machine, a wash and rinse unit comprising a fluid conduit hav-

ing a discharge opening, means for forcing a swirling stream of fluid through said discharge opening, a rotary projector comprising a hollow hub having an axial intake opening and rotatably mounted on said conduit with its intake opening in communication with the discharge opening thereof, and hollow arms extending radially from said hub and having discharge openings, a second rotary projector comprising a hollow hub rotatably mounted on the hub of the first projector, and hollow arms extending radially from said hub and having discharge openings, means for supplying fluid to said second projector comprising a pipe extending into said conduit to the center thereof and extending through the discharge opening and through the hub of the first projector and communicating with the hub of the second projector, and a deflector extending into the hub of the first projector from one side of the inner end of each of the arms of the first projector and terminating near said pipe.

19. In a washing machine, a rotary projector comprising a rotatably mounted hollow hub having an inlet opening and a pair of diametrically opposite hollow radial arms extending from said hub, one of said arms being provided along one of its sides with a plurality of spaced discharge openings, and the other of said arms being provided along one of its sides with a plurality of spaced discharge openings positioned at different distances from the axis of the hub from the openings of the first arm, the arrangement and size of said openings being such that the tendency of the reaction of the fluid discharged through the openings of one arm to turn the projector in a plane including the axis of the projector is substantially balanced by the tendency of the reaction of the fluid discharged through the openings of the other arm to turn the projector in said plane.

20. In a washing machine, a rotary projector comprising a rotatably mounted hollow hub having an inlet opening and a pair of diametrically opposite hollow radial arms of equal length and equal internal volume extending from said hub, one of said arms being provided along one of its sides with a plurality of spaced discharge openings, and the other of said arms being provided along one of its sides with a plurality of spaced discharge openings positioned at different distances from the axis of the hub from the openings of the first arm, the arrangement and size of said openings being such that the tendency of the reaction of the fluid discharged through the openings of one arm to turn the projector in a plane including the axis of the projector is substantially balanced by the tendency of the

reaction of the fluid discharged through the openings of the other arm to turn the projector in said plane.

21. In a washing machine, a rotary projector comprising a rotatably mounted hollow hub having an inlet opening and a pair of diametrically opposite hollow radial arms extending from said hub, one of said arms being provided with a plurality of spaced discharge openings of equal size, and the other of said arms being provided with a plurality of discharge openings of the same size and positioned at different distances from the axis of the hub from the openings of the first arm and located so that the sum of their distances from the axis of the hub equals the sum of the distances of the openings of the first arm from the axis of the hub.
22. In a washing machine, the combination with a support for the articles to be washed, of two projectors directed toward the articles on the support, a pump adapted to supply a washing fluid to one of said projectors, an electric motor arranged to drive said pump, a switch controlling the supply of electricity to said motor, means for supplying a rinsing fluid to the other of said projectors including a valve control-

ling the supply, and a controlling member connected to said switch and said valve and arranged to close said switch and open said valve when moved to its extreme position in one direction and to open said switch and close said valve when moved to its extreme position in the opposite direction.

23. In a washing machine, the combination with a support for the articles to be washed, of two projectors directed toward the articles on the support, a pump arranged to supply a washing fluid to one of said projectors, an electric motor arranged to drive said pump, a switch for controlling the supply of electricity to said motor, means for supplying rinsing fluid to the other of said projectors including a valve controlling the supply, and a movable controlling member arranged to close said switch and to close said valve when in its intermediate position, to open said switch when moved from its intermediate position to its extreme position in one direction, and to open said valve when moved from its intermediate position to its extreme position in the opposite direction.

In testimony whereof I have hereunto set my hand.

HENRY R. MERSELES.
